UNITED STATES PATENT OFFICE

159,406

TABLE COVER OR SIMILAR ARTICLE

Earline Brice, New York, N. Y., and Henry S. Bromley, Philadelphia, Pa., assignors to North American Lace Co., Inc., Philadelphia, Pa.

Application December 8, 1949, Serial No. 6,729

Term of patent 3½ years

(Cl. D92—26)

To all whom it may concern:

Be it known that we, Earline Brice, and Henry S. Bromley, both citizens of the United States of America and residents, respectively, of New York city, county of New York, and State of New York; and Philadelphia, county of Philadelphia, and State of Pennsylvania, have invented a new, original, and ornamental Design for a Table Cover or Similar Article, of which the following is a specification, reference being had to the accompanying drawing, forming part thereof, wherein,

We claim:

The ornamental design for a table cover or similar article, substantially as shown.

EARLINE BRICE.

HENRY S. BROMLEY.
